(57) **CLAIM**

The ornamental design for a marine electronic device display, as shown and described.

DESCRIPTION

FIG. 1 is a front perspective view of a marine electronic device display showing our new design.

FIG. 2 is a front view of the marine electronic device display of FIG. 1.

FIG. 3 is a rear view of the marine electronic device display of FIG. 1.

FIG. 4 is a left side view of the marine electronic device display of FIG. 1.

FIG. 5 is a right side view of the marine electronic device display of FIG. 1.

FIG. 6 is a top view of the marine electronic device display of FIG. 1; and,

FIG. 7 is a bottom view of the marine electronic device display of FIG. 1.

The broken lines in the drawings illustrate portions of the marine electronic device display that form no part of the claimed design.

1 Claim, 4 Drawing Sheets
